UNITED STATES PATENT OFFICE.

WILFRED F. VALLIER, OF PONTIAC, MICHIGAN.

GOVERNOR FOR INTERNAL-COMBUSTION ENGINES.

1,327,847.

Specification of Letters Patent. Patented Jan. 13, 1920.

Application filed September 24, 1917. Serial No. 192,974.

To all whom it may concern:

Be it known that I, WILFRED F. VALLIER, a citizen of the United States, residing at Pontiac, in the county of Oakland and State 5 of Michigan, have invented certain new and useful Improvements in Governors for Internal-Combustion Engines; and I do declare the following to be a full, clear, and exact description of the invention, such as 10 will enable others skilled in the art to which it appertains to make and use the same.

My invention relates to automatic governors for internal combustion engines, the device being designed primarily for preventing the motors of commercial trucks and the like, from being driven at an excessive speed, either when the motor is pulling the 15 load or when coasting down grade.

The principal object of the invention is to 20 provide a device of the class described which may be easily and inexpensively manufactured and marketed, yet one which will be highly efficient and durable and may be easily installed in connection with practically all types of commercial trucks and 25 other forms of motor vehicles.

With the foregoing general object in view, the invention resides in the novel features of construction and unique combination of 30 parts to be hereinafter fully described and claimed, the descriptive matter being supplemented by the accompanying drawings which form a part of this specification and in which:—

35 Figure 1 is a central vertical section of the improved governor, showing the positions of parts when the engine is traveling at the minimum speed;

Fig. 2 is a duplicate of Fig. 1 with the exception that it illustrates the relative positions of parts when the motor is rotating at the maximum speed permitted by the device;

Fig. 3 is a horizontal section on the plane 45 of the line 3—3 of Fig. 2; and

Fig. 4 is a detail vertical section on the plane indicated by the line 4—4 of Fig. 1.

In the drawings above briefly described, the numeral 1 designates a casing adapted to 50 be inserted between the carburetor and intake manifold of an internal combustion engine of any character, although it will be clear that the device could well be installed at any other preferred location. The casing 55 1 is provided with a fuel passage 2 having a cylindrical intermediate portion 3, an

inlet end 4 which is flared toward the carburetor, and an outlet end 5 which is increased in diameter to provide a final mixing chamber for the fuel before it is drawn 60 into the manifold for passage to the engine cylinders.

A mushroom barrier 6 is located in the mixing chamber 5 and is supported by any preferred means such as a spider 7 fitting 65 into the upper end of the passage 2, the periphery of said barrier preferably having teeth 8 which serve to break up the fuel to insure effective mixing of the gasoline and air. Coöperating with the teeth 8, are similar teeth 9 which project inwardly from the wall of the passage 2, adjacent the delivery end of said passage, the teeth 9 being preferably formed on the inner edge of a ring 10 which is secured in place by means of the 75 spider 7.

Mounted slidably within the cylindrical intermediate portion 3 of the passage 2, and contacting with the wall of said passage, is a valve sleeve 11 which is movable, by means 80 of suction, into the mixing chamber 5 for coöperation with the barrier 6, in controlling the amount of fuel passing from the device into the intake manifold. The sleeve 11 is carried by a spider 12 formed on the 85 upper end of a tubular stem 13, said stem being slidable on a rod 14 which is positioned coaxially in the casing 1 and held in place by the spider 7 and an additional spider 15 at the lower end of the device. By spring 90 means yet to be described, the valve 11 is normally lowered to permit free passage of fuel through the device, but when the suction through the passage 2, attains power 95 above a pre-determined degree, this suction acts on one or more plungers or disks 16 which are fixedly mounted on the stem 13 and held in spaced relation by any preferred means. When several of the disks 16 are employed, they are of various sizes to correspond to the taper of the end 4 of the passage 2, in which end they are located.

By positioning the disks in this tapered end of the device, it will be obvious that when they are raised by suction, the space between their 100 edges and the wall of the passage 2, will be decreased, thus initially cutting down the amount of fuel passing through the device, so that all of the fuel checking need not be done by the single valve 11. Since the fuel 110 must pass around the disks 16, it comes in intimate contact therewith, and it will thus 105

be clear that by forming teeth 17 on the edges of said disks, these teeth will serve to effectively break up the fuel to cause thorough mixing thereof, before the further action of 5 the teeth 8 and 9 takes place.

Any preferred spring means could well be employed for normally holding the sleeve 11 in lowered position, but I preferably provide a spiral spring 18, a rock shaft 19 connected to said spring and operated thereby, and a crank arm 20 having a forked end 21 straddling the stem 13 and resting on the upper lock nut of the uppermost disk 16. The spring 18 is located in a suitable casing 22 carried on the exterior of the main casing 1, the end of said spring remote from the shaft 19, being secured to a circular adjusting member 23 having a series of sockets 24 for engagement with a stud 25 in the casing, whereby turning of said adjusting member will vary the tension of the spring as occasion may require, after which, engagement of one of the sockets 24 with the stud 25, will hold said member in adjusted position. A cap 26 is threaded on the outer end of the casing 22 to retain the adjusting member 23 in place, and in order that unauthorized persons may not adjust said member, any preferred lock or seal 27 is provided to prevent removal of the cap 26.

In the operation of the improved device, with the engine running at minimum speed, all parts remain as depicted in Fig. 1, and in fact the several parts will remain in these 35 positions, until the engine has reached a pre-determined high speed. When this takes place, however, the strength of the suction through the passage 2 is so great as to act upon the plungers or disks 16, so that 40 the latter are raised against the tension of the spring 18, thus bringing the valve sleeve 11 into contact with or into close proximity to the barrier 6, so that the supply of fuel is either cut down or altogether shut off. 45 It will thus be obvious that racing of the engine is prevented, either when pulling the load, or when the engine is being driven by the vehicle in coasting down grade. Under the last-named circumstances, the sleeve 11 50 will come in contact with the barrier 6 after the engine has reached a pre-determined speed, and will thus positively cut off the supply of fuel to the motor. By this means, the motor is caused to more effectively exert 55 a braking action on the vehicle to prevent excessive speed thereof while coasting, and thus wear and tear on the brakes as well as on the vehicle in general is prevented. Throughout the operation of the device, except 60 when the valve 11 is entirely closed, the several series of teeth 8 and 9 and 17, cause effective commingling of the air and gas so that a highly volatile mixture is provided,

the final mixing taking place within the chamber 5 in which the fuel must first pass 65 outwardly around the edge of the barrier 6 and then inwardly in engagement with the teeth 9.

Although excellent results are obtained from the specific details of construction 70 shown and described, I wish it understood that within the scope of the invention as claimed, numerous minor changes may well be made.

I claim:

1. A governor for internal combustion engines comprising a fuel passage having a cylindrical intermediate portion and increased gradually in diameter from said portion toward its inlet end, the outlet end 80 of said passage being enlarged to provide a mixing chamber, a fixed central barrier in said chamber around which the fuel passes, a spring-resisted valve sleeve in sliding contact with the wall of said cylindrical intermediate portion of the passage and movable into said chamber for coaction with said barrier, a stem on said sleeve, and a suction operated disk fixedly mounted on said stem and positioned in said gradually increasing 90 portion end of the fuel passage.

2. A governor for internal combustion engines comprising a vertically disposed tubular passage member having attaching means at its ends, said passage member having a 95 cylindrical intermediate portion and being increased gradually in diameter from said cylindrical portion to its lower end, the portion of said passage member above said cylindrical portion being increased in diameter to form a mixing chamber, removable spiders extending across the ends of said passage member, a mushroom barrier carried by the upper spider and located in said mixing chamber, an open ended sleeve 100 valve slideable in said cylindrical portion of said passage member and capable of movement into contact with said barrier, a spider secured to said valve and having a depending tubular stem, a disk mounted fixedly on 110 said stem and disposed in the tapered lower end of the passage member, spring means resisting the upward movement of said valve, stem and disk, and a tie rod extending 115 from one of said removable spiders to the other and passing through said stem, whereby to secure said spiders in place and to guide the stem and associated parts.

In testimony whereof I have hereunto set my hand in the presence of two subscribing 120 witnesses.

WILFRED F. VALLIER.
